[57] CLAIM

The ornamental design for a shoe outsole and midsole, as shown and described.

DESCRIPTION

FIG. 1 is a bottom plan view of a shoe outsole and midsole showing my new design;

FIG. 2 is a cross-section taken generally along the line 2—2 of FIG. 1;

FIG. 3 is a cross-section taken generally along the line 3—3 of FIG. 1;

FIG. 4 is a cross-section taken generally along the line 4—4 of FIG. 1;

FIG. 5 is a cross-section taken generally along the line 5—5 of FIG. 1;

FIG. 6 is a cross-section taken generally along the line 6—6 of FIG. 1;

FIG. 7 is a cross-section taken generally along the line 7—7 of FIG. 1;

FIG. 8 is a side elevational view of one side of the shoe sole shown in FIG. 1;

FIG. 9 is a side elevational view of the other side of the shoe sole shown in FIG. 1;

FIG. 10 is a front elevational view of the shoe sole shown in FIG. 1; and,

FIG. 11 is a rear elevational view of the shoe sole shown in FIG. 1.

The broken line showing of a shoe upper in FIGS. 8-11 is for illustrative purposes only and forms no part of the claimed design.

FIG. 2

FIG. 3

FIG. 4

FIG. 6

FIG. 7

FIG. 8

FIG. 9

FIG. 11

FIG. 10
